(74) Attorney, Agent, or Firm — Tommy S F Wang;
Wang IP Law Group, P.C.(57) **CLAIM**

The ornamental design for a vehicle wheel, as shown and described.

DESCRIPTION

FIG. 1 is a perspective view of a vehicle wheel showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view thereof taken along the line 8-8 of FIG. 2.

The broken line portions of the vehicle wheel in FIGS. 1-3 and 7-8 represent unclaimed portions of the claimed design and form no part thereof.
